UNITED STATES PATENT OFFICE.

GEORGE E. NEUBERTH, OF NEWARK, NEW JERSEY.

TRANSOM-OPERATING DEVICE.

1,126,835.

Specification of Letters Patent.

Patented Feb. 2, 1915.

Application filed September 30, 1914. Serial No. 864,243.

To all whom it may concern:

Be it known that I, GEORGE E. NEUBERTH, a citizen of the United States, and a resident of Newark, county of Essex, and State 5 of New Jersey, have invented certain new and useful Improvements in Transom-Operating Devices, of which the following is a specification.

This invention relates to a transom operating device and is adapted to provide a device that is manually operated to close or open a transom, the operating means being of such construction that it acts to hold the transom whenever the operating means 15 stops so that no additional locking or holding operation is necessary.

In order to provide a structure as above outlined, I employ a lazy tongs which is connected at one end to the transom and at the 20 opposite end to a means for spreading and also for drawing together the end of the lazy tongs so that the tongs are extended or collapsed, as desired. This means for spreading or drawing together the lazy 25 tongs end I call the operating means, and it is made so that it holds whenever it is stopped, so that it locks the lazy tongs, and consequently the transom, against movement.

The preferred form of operating means 30 is a screw with part of its thread right-handed and part left-handed, one part being in screw-threaded engagement with the end of one lever of the lazy tongs, and the other part being in such engagement with 35 the end of another lever of the lazy tongs, so that the ends are moved together or apart, according to the direction of rotation of the screw.

The device is cheaply constructed and occupies but little space, being usually concealed by being placed in the frame of a door and extending vertically on the inside 40 of the frame with a connection through the frame to the pivot of the transom.

45 The invention is illustrated in the accompanying drawing, in which is shown one embodiment of my invention.

In said drawing, Figure 1 is a front view of part of a door frame equipped with my 50 improved transom operating device, the frame being broken away at the pivot of the transom. Fig. 2 is a side view of the invention as illustrated in Fig. 1.

55 I illustrate a portion of a door frame with the side frame 10, a cross piece or head piece 11 and a transom 12. The transom, as

shown, is pivoted at the bottom, but it will be evident that it can be pivoted at any suitable point at the sides.

The pivoted connection shown consists of 30 a plate 13 secured at the lower corner of the transom, the plate having a stem 14 with a squared end 15. The stem passes through a bushing 16 with a flange 17 at its outer end, the bushing acting as a bearing for the 65 stem, being placed in the side plate or board 18 of the door frame. An arm 19 has a square hole in one end, which hole receives the square end 15 of the stem 14, and is held in place by a washer 20 and a screw 21, 70 although other fastening means may be used.

At a suitable point in the side frame 10, is placed the operating means for manipulating the transom, in the form shown this 75 being in the form of a rod 22 which passes through an escutcheon plate 23 which has a sleeve 24 extending through the front plate or board 25 of the door frame. The rod 22 at its rear end which is screw-threaded, as 80 will be hereinafter described, is thereby provided with a shoulder 22^a which bears normally against the washer 22^b which takes up the thrust of the screw and prevents longitudinal movement of the rod. The rod is 85 provided with any suitable form of handle 26. The rod is screw-threaded, the screw being right-handed at one section thereof, as at 27, and left-handed at another, as at 28.

Beneath the screw is a guide 29 having 90 grooves 30 in its side edges, the guide being secured as by the screw 31 to a suitable support or block 32. Arranged to slide on the slide 29 are blocks 33 and 34 which have screw-threaded perforations to receive their 95 relative sections 28 and 27 of the screw-threaded rod 22. The blocks have tongues 35 to enter the grooves 30.

A lazy tongs is mounted on the blocks, the tongs consisting of lower crossed levers 36 100 and 37 secured at their bottom edges to the blocks 33 and 34, and pivoted at their centers, as at 38. Pivoted to the upper end of the lever 36 is a short lever 39, and to the upper end of the lever 37 is an upper lever 105 40 which is pivoted at 41 to the short lever 39, and extends beyond the pivot 41 and has at its upper end 42 a pivoted connection with a bar 43, the bar 43 being connected at its upper end to the arm 19, as at 44.

110 It will be evident that as the vertically disposed lazy tongs is extended horizontally

it will collapse vertically, and that when it is drawn together horizontally it will be extended vertically. Thus the blocks, when slid toward or from each other, act to vary 5 the height of the lazy tongs and by means of the bar 43 swing the lever 19, and consequently the transom 12.

The right and left-handed screws 27 and 28 draw the blocks toward each other when 10 the rod 22 is rotated in one direction, and push them farther apart when the rod is rotated in the opposite direction. When the rotation of the screw is stopped, the screw acts to hold the blocks in the positions 15 they occupy when the screw stops. The operation of the handle insures the swinging of the transom, and the cessation of such operation locks the operating mechanism, and consequently the transom, against any 20 movement. This feature obviates the necessity of using two hands to operate or lock the transom, and also prevents the swinging of the transom, as in an attempt at burglary, or in the case of a strong wind it prevents 25 rattling.

Having thus described my invention, I claim:

1. A transom operating device comprising a lazy tongs connected at the top to a transom, blocks secured to the bottom end of the 30 lazy tongs, a slide on which the blocks are movable, a right and left handed screw passing through the blocks, and a handle for operating the screw.

2. A transom operating device comprising a lazy tongs connected at the top to a transom, a slide with grooved sides, blocks 35 sliding on the slide and having tongues extending into the grooves, the blocks being connected to the bottom of the lazy tongs, and means for varying the distance between the blocks, said means also acting to lock the blocks in different relative positions.

3. A transom operating device comprising

ing a lazy tongs connected at the top to a 45 transom, a slide with grooved sides, blocks sliding on the slide and having tongues extending into the grooves, the blocks being connected to the bottom of the lazy tongs, a right and left handed screw passing through 50 the blocks and in engagement therewith, and a handle for operating the screw.

4. A transom operating device comprising an arm adapted to swing, a vertically disposed lazy tongs, a connection between 55 the top of the lazy tongs and the arm, sliding blocks at the bottom of the lazy tongs, a slide for the blocks, a right and left handed screw passing through the blocks, and a handle on the screw for rotating it.

5. A transom operating device comprising a lazy tongs consisting of crossed levers pivoted to each other at their ends and where they cross at the center, a rod extending from the end of one of the levers at the 65 top of the lazy tongs to a transom moving means, and means for varying the distance between the ends of the levers at the bottom of the lazy tongs.

6. A transom operating device comprising a lazy tongs consisting of crossed levers pivoted to each other at their ends and where they cross at the center, a rod extending from the end of one of the levers at the 70 top of the lazy tongs to a transom moving 75 means, blocks at the ends of the levers at the bottom of the lazy tongs, a slide on which the blocks move, a right and left handed screw passing through the blocks, and means for rotating the screw.

In testimony that I claim the foregoing, I have hereunto set my hand, this 28th day of September, 1914.

GEORGE E. NEUBERTH.
